DISTRIBUTING MECHANISM OF TYPOGRAPHICAL COMPOSING AND DISTRIBUTING MACHINES

Christian Augustus Albrecht, Berlin, Germany,
assignor to Mergenthaler Linotype Company,
Brooklyn, N. Y., a company of New York

Application July 26, 1933, Serial No. 682,188
In Germany August 30, 1932

3 Claims. (Cl. 199—64)

This invention relates to the distributing mechanism of typographical composing and distributing machines, such as those known commercially under the trade mark "Linotype", wherein circulating matrices are released from a magazine and assembled in line, a slug or type-bar cast from the assembled line of matrices and the matrices thereafter returned through a distributing mechanism to the magazine in which they are stored, such distribution being effected by the release of the matrices from a V-shaped distributor bar having combinations of teeth rails engaged by teeth formed in V-shaped notches on the matrices. The distributor bars heretofore proposed have been provided with toothed combinations all of equal length, or with individual toothed combinations of differing lengths to correspond with different thicknesses of matrices, and different widths of magazine channels. Recent developments have brought into use exceptionally wide matrices, with the result that all the channels of the magazines have not been utilized. For example, instead of the usual number of 90 different matrices in a complete font, 72 or 51 characters only have been employed, and in such cases, no alterations have been made to the magazines, but a certain number of the grooves or channels therein were simply not used. It has also been proposed to use devices on the magazine entrances adapted to conduct the matrices from the distributor bar to the magazine and for guiding the matrices into their respective magazine channels.

In the case of these wide matrices, some difficulty has arisen owing to the fact that they dropped from the distributor bar too late, as the distributing teeth of each matrix have been flush with the surfaces of that side of the matrix which is the following side during distribution. Consequently, the release of the matrix was effected only when its leading side had travelled so far that when the matrix dropped off it would no longer be properly guided by the partitions of the magazine entrance, or by the magazine channels.

This disadvantage has been avoided by altering the location on the distributor bar of the distributing combinations for the wide matrices, this alteration having been rendered possible through the elimination of a certain number of magazine channels and the corresponding elimination of a number of toothed combinations on the distributor bar. The necessity thus arose, in the case of multiple magazine machines, provided with an ordinary set of matrices, for a 90-character font and another set for a 72 or even a 51-character

font, of interchanging the distributor bars or, in the case of machines having matrices of respectively different kinds, of using respectively distinct distributor bars. This necessity is obviated by the present invention, owing to the fact that the appropriate matrices are each provided with a toothed combination which corresponds with the magazine channel, immediately preceding the magazine channel into which that particular matrix is to be distributed. Assuming, for example, that in the standard machines the distributor bar combinations are each 6 millimeters long, according to the invention the release of the matrices would be effected about 6 millimeters in advance of the normal combination for the respective channel, so that the matrices would drop through the magazine entrance in the proper manner, and be guided correctly therefrom into their respective magazine channels.

The accompanying drawing, which is a fragmentary front elevation of the distributing mechanism, illustrates by way of example one constructional form of the invention.

In the drawing, *a* is a part of the distributor bar, as ordinarily constructed, with the lower part V-shaped and provided with distributing teeth. The matrices are caused to travel along the distributor bar in the direction of the arrow by means of distributor screws not represented in the drawing. The respective tooth combinations terminate in the planes of the vertical dotted lines *b*. The distance between these lines therefore corresponds to the length of the distributor bar combinations. Beneath the distributor bar are arranged the magazine entrances *c* adapted to guide the matrices into the magazine *d*. In the drawing only the bottom plate of the magazine is illustrated. The magazine channels *e* are adapted to guide the matrices by their ears in the manner heretofore proposed, and are flared at the top in order to receive the matrices as they drop and lead them into the proper channel. The guiding partitions of the magazine entrances *c* are likewise spaced apart in the usual manner to such an extent that wide matrices, of which one is shown in the drawing hanging from the distributor bar, are also afforded a free passage.

The matrix illustrated in the drawing belongs to the magazine channel *g*. The distributing combination pertaining to this magazine channel would correspond with that section of the bar indicated by the arrow *h*, so that, as soon as the teeth of a matrix having a corresponding combination reach that section of the distribu-

tor bar, the matrix will be released. When ordinary matrices are used, this is effected without any difficulty.

In the case of particularly wide matrices, like that shown on the drawing, the leading edge of the matrix at this moment is in such an advanced position that said matrix could not be guided by the respective partition of the magazine entrance and therefore would not be conducted into its proper magazine channel.

According to the present invention, the matrix is provided with a distributing combination m (shown by the dotted lines in the drawing) which corresponds with the immediately preceding combination i of the distributor bar and which ap- pertains actually to the immediately preceding magazine channel K , with the result that the matrix, at the juncture indicated in the drawing, will be released from the distributor bar a and traverse the magazine entrance channel appropriate to the magazine channel g through which it will be conducted by its ears n (shown by the dotted lines in the drawing) in the ordinary manner.

Having described my invention, I declare that what I claim and desire to secure by Letters Patent is:—

1. In a typographical composing and distributing machine equipped with a distributor bar having a succession of distributing teeth combinations, a matrix with one toothed distributing combination located on the following edge thereof during the distributing movement and corresponding with a definite magazine channel, characterized by the fact that for display matrices which are wider than the length of an

individual bar combination, the selected tooth combination will correspond to that of the preceding magazine channel in order to ensure better dropping facilities for the matrices and to permit the construction of the magazine entrances with straight intermediate partitions.

2. In a typographical composing and distributing machine, the combination with a distributor bar having a succession of distributing teeth combinations and a magazine having channels each adapted to receive a matrix released from one of said distributing teeth combinations, of a matrix appropriate to a given magazine channel but of such width as to overlap the immediately preceding magazine channel and having a tooth combination corresponding with the distributor bar combination appropriate to the immediately preceding magazine channel.

3. In a typographical composing and distributing machine, the combination with a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

CHRISTIAN AUGUSTUS ALBRECHT.

40 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

45 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

50 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

55 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

60 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

65 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

70 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.

75 A typographical composing and distributing machine, comprising a distributor bar having a succession of distributing teeth combinations, a magazine having channels each adapted to receive a matrix released from one of said distributing teeth combinations, and a partitioned magazine entrance intermediate the magazine and distributor bar having its partition in vertical planes parallel with those occupied by the magazine channels, of a matrix appropriate to a given magazine channel but of such width as to overlap the immediately preceding magazine channel and having a tooth combination corresponding with the distributor bar combination appropriate to the immediately preceding magazine channel.
